UNITED STATES PATENT OFFICE.

HENRY CAVE, OF SPRINGFIELD, MASSACHUSETTS, ASSIGNOR TO DAVIS-BOURNONVILLE COMPANY, OF NEW YORK, N.Y., A CORPORATION OF NEW YORK.

EMERGENCY UNIT.

1,095,450.

Specification of Letters Patent.

Patented May 5, 1914.

Application filed June 18, 1913. Serial No. 774,345.

To all whom it may concern:

Be it known that I, HENRY CAVE, a citizen of the United States, and a resident of Springfield, in the county of Hampden and 5 State of Massachusetts, have invented certain new and useful Improvements in Emergency Units, of which the following is a specification.

This invention is an emergency unit for 10 use especially by fire departments, and is designed to provide a complete gas cutting equipment in compact portable form, ready for instant use, adapted to occupy little space on the fire truck, and to be carried 15 quickly from the truck to the place of use. The invention makes it possible to begin cutting almost immediately upon reaching the scene of operations, so that a man imprisoned behind a grating can be released 20 in an exceedingly short space of time, or any other desired cutting operation can be completed with the maximum despatch. The equipment is protected in such a way that if not used for a long period it will 25 not become damaged and can be relied upon to be ready for operation.

The accompanying drawings show two constructions by way of illustrating the invention.

30 In these views: Figure 1 is an illustration of an embodiment of the invention making use of a low pressure oxygen cylinder; Fig. 2 is a vertical section; Fig. 3 is a horizontal section taken above the casing, the cover being removed; Fig. 4 is a vertical section 35 through the casing of another construction, the parts therein being shown in elevation; Fig. 5 is a horizontal section through this construction; Fig. 6 is a view of the torch 40 partially in section and partially broken away; and Fig. 7 is a sectional view on a still larger scale showing the head and tip of the torch.

In the sectional views of the tanks no attempt has been made to indicate their contents. It will be understood that it is customary to provide the acetylene tank with a porous filler to prevent danger of explosions.

45 The unit consists of a complete gas cutting equipment, in incased, portable form, all assembled and connected up and with its adjustments fixed, so that it can be rushed to the point where needed and put 50 in operation merely by taking out the torch 55 and turning on the gases. Thus, there is no loss of time and no possibility of the men forgetting how to assemble the parts, or necessity of stopping to make adjustments.

In the construction shown in Figs. 1 to 3, there is a low pressure oxygen tank 10, which affords a substantial base on which the unit may stand, and an acetylene tank 11, inverted over the oxygen tank. The oxygen tank contains compressed oxygen under relatively low pressure; and the acetylene tank contains acetylene held in solution under pressure in the well known manner. The tanks have outlets at their proximate ends, provided with valves 12, 13 for turning the gases on and off. Reducing valves 14, 15 are connected to these outlets, and together with gages 16, 17, 18, 19 are disposed in the space between the tanks. The reducing valves are of usual or suitable construction, and as is well known they operate to maintain a uniform reduced pressure at all times at their outlet sides; and they are provided with the usual adjusting means 20, so that the gases may be delivered to the torch under uniform predetermined pressures. The gages associated with each pressure regulator are connected at opposite sides thereof, so as to show the tank pressure and the pressure in the delivery line respectively. The regulators are set for the pressures appropriate to the torch used and its adjustments, and when so set are locked by lock nuts 21, or by other suitable means, so as to guard against the pressures being changed. Both tanks are surrounded by a tubular casing 22, which is firmly fixed to the oxygen cylinder by the clamping bands 23. As shown the casing may and preferably does inclose only the upper part of the oxygen tank. The acetylene tank is suitably supported on brackets 24 projecting inward from the upper part of the casing, the acetylene tank being of considerably smaller diameter than the oxygen tank. A door 25 in the side of the casing gives access to the interior and to the valves therein, and also enables the torch 26 to be removed. The construction of the latter may be varied, but a suitable form is illustrated in Fig. 6. This torch has two connections 27, 28 at the rear, to which the oxygen and acetylene hose 29, 30 are attached, and valves 31, 32 are preferably provided to enable the operator to turn 110

off one or both gases if necessary. The acetylene passes through the pipe 33 in the handle of the torch. The oxygen is divided, as indicated, so that it passes in part 5 through the pipe 34 and in part through the pipe 35. The oxygen which flows through the pipe 35 goes to the heating jet or jets, being mingled with the acetylene from the pipe 33 to form the intensely hot flame necessary for heating the metal to such temperature as will enable the cutting or oxygen jet to work. The oxygen from the pipe 34 goes to the cutting jet. The jets are delivered from the tip 36, the construction of which is illustrated in Fig. 7. As here shown the tip has a longitudinal cutting jet passage 70, which communicates at its rear end with a space in the head into which oxygen flows from the cutting 10 oxygen pipe 34. It also has one or more heating jet passages 71, each of which communicates by oxygen and acetylene ports 72, 73 with annular grooves 74, 75 in the rear portion of the tip, these grooves in turn 15 communicating with the oxygen and acetylene pipes 35 and 33. The sizes of the passages 70, 71 and of the ports 72, 73 are all precalculated to deliver jets of certain size, composition, etc., when supplied with gases 20 under predetermined pressures, which are fixed by the setting of the pressure regulators. The flow of the oxygen for the heating jets may be regulated to an exact degree by means of a needle valve 37. This valve is 25 adjusted beforehand to the degree of opening appropriate to the size of tip 36 and the passages therein and to the pressures determined by the regulators 14, 15, and is locked in this condition by the lock nut 38. Thus 30 all the conditions are harmoniously fixed beforehand, and merely turning on the gases at the tanks establishes the heating and cutting jets in proper size, composition, velocity, etc. The torch is located in a pocket 39, 35 which is closed in front by an upward extension of the door, and it may be held against vibration by a suitable spring clip 40 on the inside of the door. The hose are wound around the acetylene tank in the upper part of the casing, above the brackets 24, and a floor 41 may be provided on which they rest. The open top of the casing is 45 shown covered by a disk 42, apertured to fit the acetylene tank. This disk may be of 50 rubber or other suitable material, and may be turned up to permit the unwinding or rewinding of the hose. Handles 43, 44 on the top of the casing and the lower end of the oxygen tank, respectively, afford convenient 55 means for carrying the unit.

When on the truck the unit is preferably disposed in an upright position. When placed on the ground it is preferably laid on its side.

60 65 In use, the unit having been brought to

within a convenient distance of the metal to be cut, the fastenings 45 of the door are released and the door thrown open, the operator grasps the torch and proceeds to the spot where the cutting is to be done, the hose unwinding as he goes, and another man turns on the valves 12, 13 at the tanks. An ordinary pyrophoric igniter 46, which normally hangs on the inside of the door, affords convenient means for lighting the heating jets. The apparatus being all in readiness for work, cutting can be begun within about fifteen seconds of placing the unit on the ground, and within two minutes four cuts can be made through one inch bars, these cuts being sufficient to move two bars of a grating to give access to a man.

Figs. 4 and 5 illustrate a construction suitable for use with a high pressure oxygen cylinder. Here the oxygen and acetylene cylinders 60 and 61 are disposed side by side, or one in front of the other, and are held in assembled relation by suitable means, such as clamping bands 62, 63. The lower handles 64 may connect these bands so as to form a sort of frame. The upper handles 65 are preferably mounted on a clamping band 66, which encircles the upper part of the oxygen cylinder, so that all of the strain of carrying is taken off the casing 67. It will be understood that the handles 65 project through suitable openings, not shown, in this casing. The casing is of oblong form in cross-section, and, as shown, may inclose only the upper parts of the tanks, though obviously it could be made to inclose the whole of the tanks if desired. It is extended upward a suitable distance above the tanks to inclose a space for the reception of the other parts. These parts are the same as in the other construction and bear the same reference numerals. The casing is suitably secured to the bands 62, 66, and is provided with a hinged door 68 to give access to the torch valves, gages, etc. In this instance the top of the casing is 100 closed, and a shelf 69 is provided at a suitable distance below it for the reception of the hose. In operation the door is opened, the torch is taken out of its clip, and as the operator moves away the hose uncoils from the shelf 69. The other man then turns on the gases at the tanks and cutting is begun. The door 68, it will be understood, is preferably a hinged door, substantially like the door 25, and extends full width all the way to the top of the casing, so that when it is open it exposes the front of the hose receptacle.

What I claim as new is:

1. A portable emergency unit, comprising a tank containing absorbed acetylene and a tank containing compressed oxygen; a cutting torch, flexible connections between the cutting torch and tanks, and pressure regulators in the respective gas lines, the fore- 125 130

- going cutting equipment having all its adjustments fixed and ready for action, and a protecting case containing the same in compact portable form.
- 5 2. A portable emergency unit, comprising a cutting equipment including a tank containing absorbed acetylene and a tank containing compressed oxygen, a cutting torch, and flexible connections between the cutting 10 torch and tanks, and a protecting case provided with handles and containing the equipment in compact portable form, whereby cutting may be instantly begun upon carrying the equipment to the scene of action.
- 15 3. An emergency unit, comprising an oxygen tank and an acetylene tank side by side, a casing oblong in cross-section receiving said tanks and extending a distance above the same, and a cutting torch, flexible connections between the same and the tanks, and pressure regulators and gages in the respective gas lines disposed within the upper part of the casing.
- 20 4. An emergency unit, comprising an oxygen tank and an acetylene tank side by side, a casing oblong in cross-section receiving said tanks and extending a distance above the same, and a cutting torch, flexible connections between the same and the tanks, and pressure regulators and gages in the respective gas lines disposed within the upper part of the casing, said casing having a door giving 25 access to the space in the upper part thereof and permitting the torch to be removed through the door to the distance per-
- mitted by the flexible connections and also enabling the gases to be turned on at the tanks, the tanks being provided with suitable valves for the purpose.
5. An emergency unit consisting of a cutting equipment comprising an oxygen tank and an acetylene tank side by side, a cutting torch, and connections between said torch and tanks, in combination with means for clamping said tanks rigidly together, and a 40 protecting case inclosing the equipment in compact portable form.
6. An emergency unit consisting of a cutting equipment comprising an oxygen tank and an acetylene tank side by side, a cutting 45 torch, and connections between said torch and tanks, in combination with a protecting case oblong in cross-section containing said equipment and having means for clamping it in relation to the tanks.
7. An emergency unit, comprising an oxygen and an acetylene tank side by side, a cutting torch, and flexible connections between the same and the tanks, in combination with a protecting case inclosing said tanks, torch 50 and connections and having a compartment above the tanks in which to dispose said connections.

In witness whereof I have signed my name in the presence of two subscribing witnesses. 65

HENRY CAVE.
